UNITED STATES PATENT OFFICE

2,615,454

CHANGE MAKER

Edward F. Leese, Everett, Wash.

Application June 10, 1949, Serial No. 98,240

5 Claims. (Cl. 133—5)

1

This invention concerns a change-maker or coin dispenser, of the general type shown in my Patent No. 2,416,486, issued February 25, 1947, and this form is shown in my Design Patent No. 159,425 of July 25, 1950.

Such change-makers are useful in a wide variety of establishments. They may be employed for instance, at subway or bus terminals, to deliver five nickels for a quarter, or ten nickels or five dimes for a half dollar. They are useful at telephone centrals for similar purposes. They are employed at cigar counters, where change is frequently desired for telephoning or for operating vending machines or amusement devices. One such establishment will require primarily nickels, and may require no other change, or perhaps only nickels and dimes. On the other hand, a different type of establishment may prefer to deliver primarily quarters, four in exchange for one dollar. Other types of establishments will want to deliver a more varied assortment of change, such as five nickels for a quarter, five dimes for a half dollar, two quarters for a half dollar, and four quarters for a dollar, and perhaps two half dollars for a dollar.

In the machine constructed in accordance with my prior patent, the machine as manufactured was inflexible. It could be designed to deliver all coins of one kind or all of a few kinds, or alternatively to deliver an assortment of various denominations, but once designed and constructed it was not possible to alter it to accommodate changing conditions. Each one built was suited only to the denominations for which it was designed, and a large stock of different combinations had to be kept to satisfy different requirements, or else each order on the manufacturer had to be handled as a special order.

It is one of the objects of the present invention to provide a change-maker of the same general character, and capable of achieving the advantages of the machine of my prior patent, having additionally the advantage of flexibility in that it is possible to change the coin hoppers or tubes, so as to deliver to users who have different requirements, change-makers with different denominations or quantities, or to enable changes to be made if conditions change. Primarily, then, it is the object herein to provide a basic machine which can be set up with little departure from manufacturing routine, in order to deliver such denominations, and such quantities of each denomination, as the particular user may require.

2

It is a further object to provide a change-maker having the capabilities and flexibility indicated, which nevertheless can be manufactured as cheaply, or more so, than the coin dispenser of my earlier patent.

It is an object of the invention to provide such a change-maker which despite the ready interchangeability of coin tubes is thoroughly solid and rugged when assembled, and not readily tampered with.

With respect to tampering, since such change-makers are usually installed in rather public places, there is a tendency on the part of certain persons to play with it, mischievously or with intent to defraud, and it is a further object of the invention to provide a change-maker having the advantages indicated above, which is entirely accessible to the operator behind a counter, but which by reason of its construction and arrangement is well protected from the passerby or loiterer at the opposite side of the counter.

It is likewise an object of this invention to provide a change-maker in a form that lends itself readily to manufacture of the principal parts by die-casting or similar operations, to the end that it may be made inexpensively yet accurately.

With such objects in mind and others, as will appear hereinafter, the present invention comprises a novel change-maker and a novel combination and arrangement of the parts thereof, as shown in the accompanying drawings, and as will be hereinafter described and claimed.

In the accompanying drawings the invention is shown in a typical form, such as is presently preferred by me.

Figure 1 is in general an elevation of the change-maker, with parts broken away and shown in section, the view-point being that of the operator.

Figure 2 is in part an elevation and in part a section, the view-point being indicated generally by the line 2—2 in Figure 1.

Figure 3 is in part an elevation and in part a section taken substantially along the line 3—3 of Figure 1.

Figure 4 is a bottom plan view, partly broken away, of one of the coin tubes, illustrating particularly the coin delivering means.

50 The support for the change-maker is a base generally indicated by the numeral 3, consisting for instance of arms 31 at its ends, a hood-like front wall or skirt 32 extending upwardly from the table whereon the change-maker is supported, and an elevated shelf 33 extending rearwardly, or toward the operator, from the upper

portion of the skirt 32. The device may be supported on low feet 38 incorporating suction cups or the like, so that these in conjunction with its weight and the weight of the coins contained by it, will not permit it to be tipped over readily or to be shifted appreciably.

The shelf 33 is of some appreciable thickness and to lighten it and save material, and to simplify the die-casting operation, it may be interiorly hollowed, so that in effect it has an upper and a lower level somewhat spaced apart. It is formed in its rear edge with notches facing rearwardly, such notches being indicated by the numerals 34 and 34a. These notches in the shelf either at the upper or at the lower level or even at both levels, are non-circularly shaped and formed preferably with parallel side edges, as are the notches 34 shown at the left in Figure 2, being of half-hexagon shape. The notches 34a at the upper level of the shelf may be, and preferably are, rounded as indicated at the right in Figure 2. Each such notch 34, 34a, is of the same size as all other such notches; they are uniform in size and shape, and this is of importance in the invention.

The coin tubes are each of suitable height and of an interior diameter to receive one particular size and shape of coin. A tube to receive nickels (such as the two at the left in Figure 1) will be of somewhat larger interior diameter, and usually taller, than a tube (the central one) which will receive dimes, but of somewhat less interior diameter than a tube (the second from the right) which will receive quarters, and so on. Externally such tubes may vary in size in their visible portions, so that the operator may determine at a glance which tube contains nickels and which contains dimes, quarters or half dollars. However, adjacent its lower end each tube 1 has a mounting section which includes barrel or flange elements 10 and 11, each of which is of uniform exterior size and shape. This mounting section of each tube, concealed when parts are operatively assembled, is of the same size and shape as the same portion of all other tubes, no matter what denomination of coin each tube is to receive. The portion 10 is formed to fit snugly within the notch 34a, and the portion 11 is formed non-circularly—for instance, of half-hexagon shape—to fit snugly within the notch 34, thereby to prevent rotation of the tube relative to the base. All such tubes and parts are readily, accurately, and cheaply formed as die-castings.

Above the barrel portion 10 of uniform diameter, and as part of its mounting section, each tube is provided with a small downwardly facing shoulder 12 which rests upon the top of the shelf 33, and with an upwardly directed shoulder 13 facing the shoulder 12, and spaced below the latter a distance equal to the thickness of the shelf 33. The thickness of the shelf, therefore, just snugly fits between the shoulders 12 and 13, and when the tube is thus seated within its notch and upon the shelf it cannot be drawn upwardly nor pushed downwardly out of position, nor can it be rotated, as already explained, but is fixedly held in position. It could be withdrawn rearwardly, but when the several coin tubes are all supported thus, each in its respective notch 34, 34a, all such tubes are held in place by a single retainer bar 2, notched complementally to the notches in the shelf and to the barrel portion 10 of each tube, which is of a thickness corresponding to that of the shelf, and overlying the rear

portion of all the tubes to constitute in effect the rear edge of the shelf itself. This retainer bar 2 is held in place by readily removable means, such as the screws 21 threaded at 35 in a lug formed integrally with the base 3.

Each coin tube is formed integrally with an enlarged lower dispensing head 14 wherein is guided a transversely slideable metering slide 4 having an aperture 41 that registers with the lower end of its coin tube. Each slide is of a depth to receive, segregate and deliver the proper number of coins from those stacked in its tube, but no more nor no less. This depth will vary for each denomination to be changed or to be delivered. The slide 4 is constructed substantially as is described in my prior patent, save that now the slide for each coin tube is mounted upon and constitutes a part of the assembly of that coin tube only. A spring or springs 42 urges the coin slide into non-delivering position, and a finger-engaged actuator 44 beneath the hood 32, but accessible from the operator's rear side, is the device by which the coin slide is moved rearwardly towards the operator into delivering position. A lower cover plate 45, secured in place by screws 46 or the like, retains the slide properly assembled with relation to the dispensing head 14 of the tube. A notch 47 in this cover plate, by engagement with the actuator 44, limits the rearward or delivery movement of the slide.

Since the notches 34 and 34a are uniform in size and shape in all tubes, and since the interfitting mounting parts 10, 11, 12 and 13, of each tube are also uniform and fit closely within the notches and above and below the shelf 33, it is evident that any given coin tube, in any combination of denominations, may be assembled in any base, and held therein by any retainer bar. Any unwanted tube may be removed and replaced with a different tube by removing the retainer bar. Initially all the tubes may be alike, or such grouping as may be desired may be attained, yet special orders are practically eliminated. One base will serve for any variety or grouping of coin tubes, and all coin tubes will fit any base. The changing of coin tubes or their removal in case of non-functioning, is a simple matter that can be done without tools, by using a coin in the slot of the screws 21 as a screw-driver. Nevertheless when parts are assembled they are held securely and firmly. The screws 21 are not accessible to tampering, nor are the actuators 44, yet everything is readily accessible to the operator.

5 I claim as my invention:

1. A change-maker comprising a base formed with an elevated shelf and having a skirt depending at its front but open at its rear side, a plurality of notches of uniform shape and size formed in the rear edge of said shelf, each having parallel sides, a like number of coin tubes each having an external upper flange near its lower end, and having an upwardly facing external shoulder spaced below said flange by the thickness of the shelf, the exterior of each tube, intermediate the flange and shoulder, being shaped to fit snugly and non-rotatively within any notch, a retainer bar notched complementally to the tubes, and of a thickness equal to that of the shelf, means to secure said retainer bar removably to the shelf, to constitute its rear edge, and coin delivering means mounted in the lower end of each tube, beneath the shelf, and operatively engageable only from the open rear side of the skirted base.

2. A change-maker comprising a base formed with an elevated shelf having in one edge a plurality of notches of uniform size and shape, a like number of coin tubes each of an internal diameter peculiar to a single size of coin, a mounting section formed on the exterior of each tube, of uniform size and shape to correspond to and fit snugly within any of said notches, whereby all tubes are disposed uprightly relative to said shelf, two members projecting laterally from each tube's mounting section, one in position to engage the upper surface of the shelf and thereby to support the tube, and the other beneath the lower surface of the shelf to prevent upward separation of the tube from the shelf, means overlying the tubes to retain them within their respective notches, a dispensing head at the lower end of each tube, and a coin-delivering element shiftably mounted in the dispensing head of each tube, apertured to receive the size of coin stored in such tube, and of a height to receive and dispense a predetermined number thereof.

3. A change-maker as in claim 2, wherein the two members which project laterally from each tube are formed as two shoulders encircling such tube at a spacing corresponding to the thickness of the shelf, and snugly fitting over and under the shelf, respectively, to retain the tube against any endwise movement when the tube is overlaid by the retaining means.

4. A change-maker as in claim 2, wherein the tube-retaining means is formed as a retainer bar notched along an edge complementary to the shelf and to the several tubes, and cooperating with the shelf to surround closely the mounting section of all the tubes, and releasable means to secure said retainer bar to the shelf, as a continuation of the shelf.

5. A change-maker comprising a base formed with an elevated shelf of given thickness having in one edge a plurality of notches of uniform size and shape, a like number of coin tubes each of an internal diameter peculiar to a single size of coin, a mounting section formed on the ex-

terior of each tube, of uniform size and shape to correspond to and fit snugly within any of said notches, two shoulders projecting from the mounting section of each tube, spaced apart a distance equivalent to the thickness of the shelf, to engage the upper and lower surfaces of the shelf and thereby to support the tube, and all tubes alike, uprightly within their notches, a retainer bar of a thickness corresponding to that of the shelf, and notched along one edge complementally to the shelf and to the tubes supported thereon, and cooperating with the shelf to snugly surround the mounting portion of each tube, and to be engaged by the shoulders of each tube, thereby to prevent, in cooperation with the shelf, endwise-movement of any tube, releasable means to secure said retainer bar to the shelf, as a continuation thereof, a dispensing head at the lower end of each tube, and a coin-delivering element shiftably mounted in the dispensing head of each tube, apertured to receive the size of coin stored in such tube, and of a height to receive and dispense a predetermined number thereof.
